UNITED STATES PATENT OFFICE.

GUY GARFIELD STAINES, OF ALBION, NEW YORK.

BARREL-HOOP-REPAIR DEVICE.

1,381,760.

Specification of Letters Patent. Patented June 14, 1921.

Application filed August 7, 1920. Serial No. 401,975.

To all whom it may concern:

Be it known that I, Guy G. Staines, a citizen of the United States, residing at Albion, in the county of Orleans and State 5 of New York, have invented certain new and useful Improvements in Barrel-Hoop-Repair Devices; and I do declare the following to be a full, clear, and exact description of the invention, such as will enable others 10 skilled in the art to which it appertains to make and use the same.

This invention relates to an improved repair device for use in repairing hoops which have come apart or become broken, and one 15 object of the invention is to provide a hoop repairing device so constructed that it may be supported vertically upon a barrel and the hoop to be repaired held in engagement with an anvil at the upper end of the standard forming part of the device, thus permitting nails to be driven through the overlapping portions of the hoops and crimped 20 against the anvil.

Another object of the invention is to so 25 construct this device that the lower portion of the barrel may be engaged by clips at the base of the standard and the upper portion of the barrel by a clamp carried by the standard and passing through a slot extending longitudinally of the standard to permit of adjustment according to the height 30 of the barrels.

Another object of the invention is to so 35 construct this device that it will be simple in construction and strong and durable and adapted for connection with a barrel of a conventional construction of approximately a standard size.

This invention is illustrated in the accompanying drawings, wherein:

Figure 1 is a view showing the improved device in front elevation and connected with a barrel, a portion of the barrel being shown in elevation.

Fig. 2 is a view showing the device in rear elevation.

Fig. 3 is a vertical sectional view taken along the line 3—3 of Fig. 1.

Fig. 4 is a perspective view of one of the 50 hoop engaging clamps connected with the upper portion of the standard.

This improved hoop repairing device is provided with a standard 1 which is formed of wood and is of sufficient height to extend 55 above the upper end of the barrel 2 with

which the device is to be connected. This standard carries a block 3 at its lower end for engaging the side of the barrel adjacent its lower end and holding the lower portion of the standard in spaced relation to the barrel. Spacing blocks 4 are provided adjacent the sides of the standards for engaging the barrel adjacent its upper end and it will thus be seen that the device may have firm engagement with the side of the barrel when connected therewith as shown in Fig. 3. In order to connect the standard with the barrel, there has been provided upper and lower clamps for engaging the upper and lower ends of the barrel. The lower clamps or 60 hooks 5 are formed of strong metal and are secured to the lower end portion of the standard. These barrel engaging hooks extend beyond the rear or inner face of the standard and will engage the barrel as shown 65 in Fig. 3 with the barrel fitting between the bills 5' of these hooks and the spacing block 3. The clamp 6 for engaging the upper 70 portion of the barrel is in the form of a bolt which extends through a longitudinally extending slot 7 formed in the upper portion of the standard above the block 4. This bolt or clamp 6 is bent adjacent its head so that an arm 8 is provided which will extend 75 downwardly with the head of the bolt engaging the barrel. The bolt may have movement longitudinally of the standard in the slot 7 and therefore the upper clamp may be moved vertically of the standard according to the height of the barrel. After 80 the upper clamp has been moved to properly engage the barrel, the wing-nut 9 will be tightened thus drawing the upper clamp into tight engagement with the barrel and securely holding the standard in engagement 85 with the barrel.

When the overlapping end portions of a barrel hoop become disconnected or when a barrel hoop becomes broken it is necessary to place the end portions in overlapping relation and then drive securing nails through the overlapping end portions of the hoop. A shoe or anvil 10 has therefore been placed upon the upper end portion of the standard, the shoe or anvil being provided with a longitudinally curved upper face and having a depending side flange 11 through which securing bolts 12 are passed. These bolts pass through the standard and are provided with the usual securing nuts 13 so that the bolts 110

can be drawn tight to securely but releasably hold the anvil in place. A plate 14 is placed upon the bolt 12 before the securing nuts 13 are put in place and this plate extends transversely of the upper end portion of the standard and across the shank of a hook engaging clamp 15. This clamp 15 is formed of spring steel or any similar resilient metal and has at its lower end a cleat 16 for holding the clamp against vertical movement when driven into the standard. The arm 17 at the upper end of this clamp 15 extends across the anvil in diverging relation to the same and therefore when the overlapping end portions of a barrel hoop 18 are passed beneath the arm 17 they will be tightly gripped by this clamping arm and held in the overlapping relation in tight engagement with the anvil. It will thus be seen that with the end portions of the hoop held in overlapping relation, the securing nails may be driven through the overlapping end portions of the hoop and these nails will be turned and clenched in the hoop. Therefore, a broken hoop can be easily and quickly repaired and the hoop formed the desired size. It will be further noted that the device is so constructed that it may be connected with a barrel which happens to be near at hand in an orchard or packing room and further that the device is very simple in construction and can be readily carried from one place to another and set up for use.

I claim:

1. A repair device for a barrel hoop comprising a standard, clamping means at the lower end of the standard for engaging the lower portion of a barrel, adjustable clamping means carried by the standard for engaging the upper portion of a barrel, a head for the standard having a longitudinally curved upper face and constituting an anvil, and means for engaging overlapping end

portions of a hoop and holding the same upon the curved upper face of the anvil. 45

2. A device for repairing barrel hoops comprising a standard, spacing blocks carried by the standard for engaging upper and lower portions of a barrel and holding the body of the standard in spaced relation to a barrel, clamping means carried by the standard for engaging upper and lower ends of a barrel and releasably holding the standard in engagement therewith, an anvil upon the upper end portion of the standard, and means 50 for holding the overlapped end portions of a barrel hoop upon the anvil. 55

3. A repair device for a broken barrel hoop comprising a standard, clamping means permanently connected with one end portion of the standard for engaging one end of a barrel with the standard extending longitudinally of the barrel, a clamping bolt passing through a longitudinally extending slot in the standard and having one end portion 60 bent to engage the second end portion of the barrel when the clamping bolt is tightened, an anvil carried by the standard and having a curved upper face, and means for engaging overlapping end portions of a hoop and 65 holding the same upon the anvil. 70

4. A repair device for a barrel hoop comprising a standard, an anvil carried by the standard and having a depending side flange, a work engaging clamp having an arm extending across the anvil and a shank extending in engagement with the standard, securing means passing through the depending flange of the anvil, and a cross strip carried by the securing means and extending across 80 the depending shank of the work engaging element to hold the work-engaging element in place. 75

In testimony whereof I have hereunto set my hand.

GUY GARFIELD STAINES.
